UNITED STATES PATENT OFFICE.

ROBERT E. HALL, JR., OF TIFTON, GEORGIA.

DESIGN FOR A COUPON.

59,890.

Specification for Design.

Patented Dec. 6, 1921.

Application filed April 25, 1921. Serial No. 464,471. Term of patent 7 years.

To all whom it may concern:

Be it known that I, ROBERT E. HALL, Jr., a citizen of the United States, residing at Tifton, in the county of Tift and State of Georgia, have invented a new, original and ornamental Design for a Coupon, of which the following is a specification, reference being had to the accompanying drawing, forming part thereof.

The figure is a view in plan of a coupon showing my new design.

I claim:

The ornamental design for a coupon as shown.

ROBERT E. HALL, JR.
